INTERLOCKING SYSTEM FOR RAILROADS

Sedgwick N. Wight, Rochester, N. Y., assignor to
General Railway Signal Company, Rochester,
N. Y.

Original No. 1,824,181, dated September 22, 1931,
Serial No. 379,176, July 18, 1929. Application
for reissue September 9, 1932, Serial No. 632,437

8 Claims. (Cl. 246—3)

This invention relates to interlocking systems, and more particularly to a novel interlocking system in which all of the interlocking is carried on directly between traffic controlling devices 5 rather than between levers controlling such traffic controlling devices.

As understood by those skilled in the art of interlocking practice, it is essential that no traffic controlling device should be permitted to assume a particular indicating or control condition unless all conflictable traffic controlling devices are in a non-conflicting condition. In mechanical interlocking plants it is found expedient to have the interlocking mechanism associated with 15 the levers, this for mechanical and structural reasons. During the evolution of interlocking practice this theory of interlocking levers mechanically has been carried on to interlocking plants employing electrically controlled traffic 20 controlling devices.

In accordance with the present invention it is proposed to leave the control levers free for movement in any direction at all times, and to so interlock the circuits controlled by these levers, 25 through contacts controlled by the various traffic controlling devices, that it is impossible to supply clearing or operating energy to any particular traffic controlling device unless all of the conflictable traffic controlling devices have been 30 operated to their non-conflicting positions or conditions.

Another object of the present invention resides in the provision of means for indicating in the 35 tower if a particular traffic controlling device cannot be operated by reason of the fact that there is a conflictable traffic controlling device in its conflicting position or condition.

Other objects, purposes and characteristic features of the invention will in part be described 40 hereinafter and in part be obvious from the accompanying drawing.

In describing the invention in detail reference will be made to the accompanying drawing which 45 conventionally shows the control circuits and devices of a particular way station together with a lever and indicating apparatus located in the dispatcher's office.

Referring to the drawing the main track of a 50 railway system has been shown by track rails 1, divided into track sections by insulating joints 2, of which the track sections A, B and C only have been shown. From this main track diverge the routes D and E, comprising rails 3 and 4 respectively. Each of these track sections is provided 55 with the usual track circuit, of which the track

section A has a track circuit including the battery 5 and the track relay T, the track circuit of section B includes the track relay T¹ and the battery 6, the track section C has a track circuit including the battery 7 and the track relay T², 5 and the track circuit of section E contains the track relay T³ and the track battery 8.

The diverging route E is connected to the main track through the medium of the track switch S¹ and the diverging route D is connected to the 10 main track through the medium of the track switch S². At the entrance to the diverging route E is located a main signal ME and a take-siding signal DE, whereas at the entrance to the diverging route D there is located a main west-bound 15 signal MW. The switches S¹ and S² are provided with the usual switch box contacts, which contacts are included in the interlocking circuits more clearly described in connection with the 20 operation of the system. Also, if desired, these switches S¹ and S² may be operated by switch machines controlled by control relays and indicating track circuit occupancy in a manner as 25 shown in the application of F. L. Dodgson, Ser. No. 187,508, filed April 29, 1927.

In the interlocking tower, the entire interlocking plant or plants are preferably reproduced in 30 miniature, and for convenience only that part of the railway system shown in the drawing has been shown reproduced in miniature in the interlocking tower. This miniature track layout shows the diverging route e and the diverging route d as well as the miniature wayside signals 35 me, de and mw. In the particular arrangement shown, the main signal ME is controlled by lever L¹ and the take-siding signal DE is controlled by the lever L². It is believed that the novel features and operating characteristics of the system 40 will be best understood by considering the operation of the system.

Operation

Although the switches S¹ and S² may be either 45 hand-operated from a local switch stand, or operated from the interlocking tower either mechanically or electrically, it is for convenience assumed that these track switches are operated from the dispatcher's office by mechanical means such as pipe lines or cables.

Let us assume that both of these track switches 50 S¹ and S² assume the main track position. Let us further assume that the operator wishes to clear the main signal ME. In order to do so the operator will operate the lever L¹ to its dotted proceed position, thereby completing the follow- 55

ing circuit:—beginning at the tower battery 10, wire 11, lever L¹, wires 12 and 13, winding of the indicating relay 1R, line wire 14, contact 15 on the west-bound signal MW, wire 16, front contact 17 of the track relay T², wire 18, switch box contact 19, wire 20, front contact 21 of the track relay T¹, wire 22, winding of the control relay 1Z, wire 23, switch box contact 24, wire 25, front contact 26 of the track relay T, wire 27, common return wire C to the negative terminal of battery 10. Under this assumed condition of the various track relays and switch box contacts in the circuit just traced, the control relay 1Z will assume its energized position. With the control relay 1Z assuming its energized position, the main signal ME is free to assume its proceed position, providing traffic conditions in advance thereof are clear. In this connection it may be pointed out that the circuit just traced in itself checks traffic conditions to the next opposing signal in advance, but in some cases the signal ME, may if desired, be prevented from assuming its proceed position because there is another train in the next section ahead of the track section C by the inclusion of suitable signal blade or line relay contacts in said circuit. With the circuit through the control relay 1Z closed, this on the assumption that there is no conflicting route set up, the indicating relay 1R will assume its energized position, thereby closing an energizing circuit through the indicating lamp me, which circuit includes the front contact 30 of the indicating relay 1R.

Should now an east-bound train accept the signal ME in its proceed position, and should it move into the track section A the track relay T would assume its de-energized position, thereby breaking the energizing circuit for the relay 1Z at the contact 26 of the track relay T, and in turn effect deenergization of the indicating relay 1R and extinguishment of the indicating lamp me. Similarly, occupancy of the track sections B and C will effect extinguishment of the indicating lamp me through the medium of the opening of contacts 21 and 17 of the relays T¹ and T². The operator will thus be informed of the entrance of the train into the section of track A, B, and C.

Let us now assume that the operator returns the lever L¹ back to its normal position, and through the medium of a large lever, (not shown) which acts through mechanical means to operate the track switch S¹, operates the switch S¹, to the take-siding position. Under this condition the signal ME cannot be cleared because the switch box contact 24 now assumes the dotted position, and the circuit for the control relay 1Z for this reason cannot be completed.

Let us now assume that the operator moves the lever L² to its dotted position. Under this condition the following circuit is closed provided the track section E and the fouling track circuit A is not occupied by another train:—beginning at the battery 10, wires 11 and 35, lever L², wires 36 and 37, winding of the indicating relay 2R, wire 38, front contact 39 of the track relay T³, wire 40, winding of the relay 2Z, wire 41, switch box contact 24, wire 25, front contact 26 of the track relay T, wire 27, and common return wire C to the negative terminal of battery 10. With the control relay 2Z assuming its energized position, due to completion of this circuit the dwarf signal DE will assume the proceed position through the medium of the front contact 45 of the control relay 2Z. It is thus seen that the dwarf signal DE cannot assume its proceed position unless the

track switch S¹ is in the take-siding position and the track relays T and T³ are in their energized position.

Should either the track switch E or the fouling track circuit A be occupied at the time that the operator moves his lever L² he will be informed of that fact by reason of failure of the indicating lamp de to be illuminated, it being understood that with energizing current for the control relay 2Z actually flowing through indicating relay 2R connected in series therewith, the relay 2R will also assume its energized position, and will illuminate the indicating lamp de through a circuit including the front contact 46 of the indicating relay 2R. Although the track switches S¹ and S² have been assumed to be operable from the tower mechanically, these track switches may be operated by switch machines protected against dangerous operation by approach locking circuits and detector locking circuits, all in a manner as described in detail in my prior application Ser. No. 120,423, filed July 3, 1926, to which reference may be had, if desired.

Applicant has thus provided an interlocking system in which all of the features of interlocking are located locally with respect to the traffic controlling devices, and in which the control levers are free to be moved at any time, and in any manner, the entire protection against operating traffic controlling devices to positions conflicting with routes then set up being taken care of by local interlocking circuits including contacts of conflictible traffic controlling devices. Further, the system proposed indicates to the operator that a certain route cannot be set up in the event that such is the case, by failure of the indicating lamp on the miniature track layout to be illuminated in response to movement of the corresponding lever. Also, these same indicating lamps inform the operator of the passage of a train over the route set up, in that they indicate when the signal at the entrance to such route assumes its danger position in response to the movement of trains into such route.

Having thus shown and described one rather specific embodiment of the present invention, it is desired to be understood that the particular embodiment illustrated has been shown for the purpose of exemplifying the invention and facilitating description thereof, and has not been selected for the purpose of showing the exact construction and circuit arrangement preferably employed in practicing the same, and that various changes, modifications and additions may be made to adapt the invention to any particular track layout to which the invention is to be applied, all without departing from the spirit or scope of the invention, or the idea of means underlying the same, except as demanded by the scope of the following claims.

What I claim as new is:—

1. In an interlocking system, the combination with a plurality of levers in an interlocking tower free to be moved to any position at any time, a traffic controlling device for each lever controlled by such lever and located at a distant way station, a control relay associated with each traffic controlling device for controlling the operative condition of such device, a circuit controlled by one of said levers for a particular control relay including contacts mechanically operated by other and conflicting traffic controlling devices closed only when such conflicting traffic controlling devices are in their non-conflicting positions.

and indicating means in said interlocking tower included in series in said circuit at a point in said tower for indicating the continuity of said circuit through said particular control relay.

- 5 2. In an interlocking system, the combination with a plurality of levers in an interlocking tower free to be moved to any position at any time, a traffic controlling device for each lever controlled by such lever and located at a distant way station, 10 a control relay associated with each traffic controlling device for controlling the operative condition of such device, a circuit controlled by one of said levers for a particular control relay including contacts mechanically operated by other 15 and conflicting traffic controlling devices closed only when such conflicting traffic controlling devices are in their non-conflicting positions, an indicating relay in said interlocking tower included in series in said circuit at a point in said 20 tower and assuming its attracted position when said circuit through said control relay is energized, and an indicator controlled by said indicating relay and rendered active when said indicating relay assumes its attracted position.
- 25 3. In an interlocking system, the combination with a plurality of levers in an interlocking tower free to be moved to any position at any time, a traffic controlling device for each lever controlled by such lever and located at a distant way station, 30 a circuit controlled by one of said levers for controlling a particular traffic controlling device including contacts controlled by other and conflicting traffic controlling devices closed only when such other conflicting traffic controlling devices 35 are in their non-conflicting positions, and means included in series in said circuit at a point in said interlocking tower for indicating at said tower the flow of current through said particular traffic controlling device and thereby indicating if any 40 of said conflicting traffic controlling devices are in a conflicting position.
4. In an interlocking system, the combination with a plurality of levers in an interlocking tower free to be moved to any position at any time, a traffic controlling device for each lever controlled by such lever and located at a distant way station, a control relay associated with each traffic controlling device for controlling the operative 45 condition of such device, a circuit controlled by one of said levers for controlling a particular control relay including contacts associated with other and conflicting traffic controlling devices closed only when such conflicting traffic controlling devices are in their non-conflicting positions, and indicating means in said interlocking tower and included in series in said circuit at a point in said tower for indicating the continuity of said circuit through said indicating means and 50 through said particular traffic controlling device.
5. In an interlocking system, the combination with a plurality of levers in an interlocking tower free to be moved to any position at any time, a traffic controlling device for each lever controlled by such lever and located at a distant way station, a control relay associated with each traffic controlling device for controlling the operative 55

condition of such device, a circuit controlled by one of said levers for a particular control relay including contacts associated with other and conflicting traffic controlling devices closed only when such conflicting traffic controlling devices are in their non-conflicting positions, an indicating relay in said interlocking tower and included in series in said circuit at a point in said tower and assuming its attracted position when said circuit is energized, and an indicator in said 10 interlocking tower and controlled by said indicating relay and rendered active when said indicating relay assumes its attracted position to thereby indicate the condition of one traffic controlling device over the same circuit used for 15 controlling another traffic controlling device.

6. In an interlocking system, the combination with a plurality of levers in an interlocking tower free to be moved to any position at any time, a wayside signal for a particular lever and located at a distant point, a track switch and an opposing signal ahead of said signal, a circuit controlled by said particular lever for controlling said first mentioned signal and including contacts controlled respectively in accordance with 25 the position of said track switch and the position of said another signal in advance, said contacts being closed only if said another signal in advance is at stop and said track switch is in a non-conflicting position, and indicating means in said 30 interlocking tower included in series in said circuit at a point in said tower for indicating if said contacts are closed.

7. In an interlocking system, the combination with a plurality of levers in an interlocking office 35 each free to be moved to any position at any time, a wayside signal for governing traffic in a particular direction over a stretch of track, another wayside signal for governing traffic in the opposite direction over said stretch, a circuit for 40 controlling one of said signals including a contact of one of said control levers and a contact closed only when the other signal is in its stop condition, and indicating means in said interlocking tower and included in series in said circuit at a point in said tower for indicating the continuity of said circuit and in turn the indicating condition of said other wayside signal.

8. In an interlocking system, the combination with a plurality of levers in an interlocking office 50 each free to be moved to any position at any time, a wayside signal for governing traffic in a particular direction over a stretch of track, another wayside signal for governing traffic in the opposite direction over said stretch, a circuit controlled by one of said levers and for controlling one of said signals and including contacts closed only if said stretch of track is unoccupied and said other signal is in its stop condition, and indicating means in said interlocking tower and 55 included in series in said circuit at a point in said tower for indicating the continuity of said circuit and in turn the occupancy of said stretch of track if said other signal is in the stop condition.
